UNITED STATES PATENT OFFICE.

SEBASTIAN RITTY, OF DAYTON, OHIO.

IMPROVEMENT IN STEAM-BOILERS.

Specification forming part of Letters Patent No. 141,172, dated July 22, 1873; application filed February 6, 1873.

To all whom it may concern:

Be it known that I, SEBASTIAN RITTY, of Dayton, in the county of Montgomery and State of Ohio, have invented certain Improvements in Steam-Boilers, of which the following is a specification:

My invention relates to a manner of securing, beneath and in connection with an ordinary steam-boiler, a series of tubes, which embrace the furnace and combustion-chamber, and which extend the entire length of the former.

The figure is a side elevation of the improved steam-engine boiler.

A represents an ordinary cylindrical steam-boiler, constructed in the usual manner. H is the man-head, and D a series of tubes. A series of holes are drilled through that part of the boiler embraced by the part or division K, thus securing a communication between the cylindrical boiler and tubes. O is the furnace-front, having a door, C, the frame of which extends through the supporting-plate E. The division K is a closed vessel riveted onto the boiler, has parallel sides, and extends downward beneath the furnace. It has an orifice through its center, indicated by dotted lines, for the products of combustion to pass through.

An arm-hole is shown at L. B represents a series of tubes with closed outer ends, and the

inner open ends of which are secured to the central division, the outer ends being supported by the plates E and F. The rear supporting-plate is held in position by the rivets m, which secure it to the plate G, and the front plate E is supported in like manner.

The rear plate G serves to give direction to the products of combustion, and, in part, may be substituted by a brick wall. The tubes occupy all the space from beneath the furnace to the boiler, with the exception of furnace-space. These tubes may serve as grates, or grate-bars may be placed within the tubes.

The operation may be described thus: The boiler is supplied with water; a fire being built within the furnace, the products of combustion pass through the central division, are diverted at the back through the flues of the boiler, thence to the chimney.

The exposure of numerous tubes to the action of fire generates steam more effectually than is done with the ordinary steam-boiler.

What I claim as my invention is—

The arrangement of the boiler A, hollow division K, and tubes B B, substantially as described.

SEBASTIAN RITTY.
